UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

FIBER RAILWAY SIGNAL-TORPEDO.

1,242,663.

Specification of Letters Patent.

Patented Oct. 9, 1917.

Application filed April 4, 1916. Serial No. 88,766.

To all whom it may concern:

Be it known that I, FRANK DUTCHER, a citizen of the United States, residing at Versailles, in the county of Allegheny and State 5 of Pennsylvania, have invented certain new and useful Improvements in Fiber Railway Signal-Torpedoes, of which the following is a specification, reference being had therein to the accompanying drawing.

10 My invention relates to improvements in a fiber railway signal torpedo, which has its case composed of paper or other fibrous material to produce a non-flying torpedo.

The primary object of my present invention is to provide a fiber torpedo case composed of an inner and outer fiber case and an improved manner of attaching the rail-engaging member to the outer case.

In the accompanying drawings:

20 Figure 1 is a perspective view of my improved torpedo.

Fig. 2 is a section taken transverse the outer case with the inner case and rail-engaging member shown in full lines.

25 Fig. 3 is a perspective view of a cylindrical fiber tube out of which the inner tube is constructed.

Fig. 4 is a view showing the manner of threading the rail-engaging member through 30 the outer case.

Fig. 5 is a slight modification as to the location of the rail-engaging strap in the outer case.

Fig. 6 is a perspective view of the inner 35 explosive containing case.

Referring now to the drawing, 1 is an outer tubular fiber case of a flattened rectangular form with open ends 2, and 3 is an inner fiber case composed of a flattened tube.

40 The inner explosive containing case 3 is formed from a tube 4, and this tube is preferably first formed from a sheet cylindrically formed, as shown in Fig. 3. This cylindrical tube is afterward flattened and the explosive (not shown) placed in the center thereof, and the ends of the tube extend beyond the explosive and are flattened and doubled back under the explosive, as shown in Fig. 6. The outer tubular case 1, as 45 shown, incloses the inner case and serves to hold the flattened and doubled ends 5 in their folded positions. By providing the explosive containing case with the extended flattened and doubled back ends 5, a water-tight

closure is formed for the explosive within 55 the case 3.

No claim is made herein for the form of the inner explosive containing case and the inclosing of it by the outer case, as this is made the subject-matter of a copending application and need not be further described herein, so far as the present invention is concerned.

My present improvement relates to the manner of applying the rail-engaging member 65 to the outer case.

In Figs. 1 and 2 the rail-engaging member 6 is composed of a spring, while in Figs. 4 and 5, the rail-engaging member 7 is a lead strap.

In carrying out the present improvement, the outer tube 1 is provided with openings 8, through which the rail-engaging member is passed. In applying this rail-engaging member, the outer case 1 is flattened as 70 shown in Fig. 4, at a point centrally between the openings 8, which bring these openings in alinement and the rail-engaging member is then threaded through these openings as shown in Fig. 4, whether the member be of 75 a spring strap or a lead strap. After the strap is threaded through these openings, the tube is flattened at right angles to that shown in Fig. 4, which brings it into the shape shown in Figs. 1, 2 and 5, with the 80 strap in position and ready to have the inner explosive containing case placed therein, as shown.

When a spring strap 6 is used, it may be provided with the kinks 9, which will hold 90 the strap against endwise movement, the said strap being of spring steel the passing of the train thereover will break the spring so that it will fall apart. This formation of the spring itself is not claimed herein as it 95 is the subject-matter of my Patent No. 1,009,139, dated November 21st 1911.

In Fig. 5 the outer case 1 has its rail-engaging strap openings 8' so located as to be at the sides of the case substantially instead 100 of in its bottom between its sides as shown in Figs. 4 and 5.

By constructing the outer case of a collapsible fiber member with the strap openings 8 located to register when the tube is 105 collapsed, a convenient manner of attaching the rail-engaging member to the outer case is provided which obviates what has here-

2
tofore been a difficult problem, viz., the threading of a rail-engaging strap through openings in a torpedo case. It enables the rail-engaging strap to be very quickly attached to the torpedo and when attached an intermediate portion thereof lies between the inner and outer case and serves to lock it in position.

Having thus described my invention, what 10 I claim and desire to secure by Letters Patent is—

1. The method of making a fiber torpedo consisting in providing a collapsible fiber tube having perforations, arranging the said 15 perforations whereby they will register when the tube is collapsed, collapsing the tube, passing a rail engaging member through the registering perforations, restoring the collapsed case to tube form, and inserting an explosive containing 20 case within the tube.

Copies of this patent may be obtained for five cents each, by addressing the "Commissioner of Patents, Washington, D. C."

2. The method of making a fiber torpedo consisting in providing a collapsible fiber tube having perforations spaced apart, arranging the said perforations whereby they will register when the tube is collapsed, collapsing the tube, passing a rail engaging member through the registering perforations, restoring the collapsed case to tube form, and inserting an explosive containing case within the tube thereby situating an intermediate portion of the rail engaging member between the explosive containing case and the tube.

In testimony whereof I hereunto affix my signature in the presence of two witnesses.

FRANK DUTCHER.
